UNITED STATES PATENT OFFICE.

HERMANN BÄURLIN, OF AARBURG, SWITZERLAND.

ELECTRIC-ARC LAMP.

SPECIFICATION forming part of Letters Patent No. 576,802, dated February 9, 1897.

Application filed May 11, 1896. Serial No. 591,120. (No model.)

To all whom it may concern:

Be it known that I, HERMANN BÄURLIN, a citizen of Switzerland, and a resident of Aarburg, in the canton of Aargau, Switzerland, have invented certain new and useful Improvements in Regulators for Electric-Arc Lamps, of which the following is a specification.

My invention relates to an improved mechanism for regulating electric-arc lamps, and especially to that kind of regulating mechanism where the regulating electromagnet is excited by a shunt-current. The arrangement provided for this purpose is fully and clearly described in the accompanying drawings, in which—

Figure 1 is a central vertical section through a complete arc-lamp provided with the new regulating device. Fig. 2 is a central vertical section at right angles to that of Fig. 1. Fig. 3 is a plan view of the lamp with the cap removed, and Figs. 4 to 13 are details of various parts of the lamp.

The cylindrical sheet-metal casing A carries at its lower end the reflector B, and is also fixed by screws *a* to a ring-shaped bottom C, having a diametrical cross-piece C', said ring being connected by the strips C² with the plate D, upon which the regulating mechanism is mounted and which is covered by a cap E, fastened to the circumference of plate D by screws *e*.

Upon the plate D is mounted a horseshoe electromagnet F, whose armature G consists of two metal plates g g, connected by stay-bolts g' g² g³, and a cross-piece g⁴, said armature being pivoted between two centering-screws d d, supported by the pins d' d'. Each of the plates g has at its extremity opposite to the cores of the magnet a soft-iron piece f, serving as the armature proper, to be acted upon by the electromagnet. The pieces f f are connected by a cross-bar f', carrying in its middle part a rod f², jointed to the piston h, which fits into a cylinder h', this arrangement serving as an air-cushion brake or damper. To the other extremity of plates g g is attached a spiral spring L by means of the pin g'. Said spring, being fastened also to the fixed plate D, tends to keep the other extremity of the plates g g and the armature-pieces f f at a distance from the electromagnet.

Between the side plates g g, forming a rocking lever, is placed a clockwork operated by the weight M, suspended on a cord m. This cord passes over the larger pulley m' and a smaller one m² and connects to the end of the rod N, guided by a tube N², which is fastened to but insulated from the cross-piece C' of the ring C by means of a bushing c⁴. This rod N serves as holder for the lower carbon of the arc-lamp, for which purpose it is provided with a clamp N', fixed to the lower end of rod N. The top of this rod is guided by a cross-head N², insulated from the rod N by a bushing N² and passing by means of the slots n n between the guiding-bars n² n², connecting the base-ring C and the plate D. In the same manner are provided parallel to the vertical axis of the weight M, to the right and left, the guiding-bars M' M', passing through suitable holes or slots of the pins M² M² in the weight M, which latter carries a clamp M⁴, secured in an insulating-bushing M⁶ therein to hold the upper carbon and insulate it from the mechanism for regulating the feed adjustment of the carbons.

To the clamp M⁴ and to the top of the bar N are attached the insulated conducting-wires o o' in a suitable manner and are also affixed to the terminals o² o³, from which also the shunt-circuit branches off, passing around the coils of the electromagnet, as will be hereinafter described. This circuit is indicated by the wires p p', Fig. 3. The terminals o² o³ serve also for connection with an external circuit, from which the lamp is to derive its current. For engagement of the clockwork there is provided on the axis of rope-pulley m' a pinion Q, geared to a train of gear-wheels, the last one having an escapement-wheel L, which gears into the escapement-wheel Q², fixed on the axis R', the latter being provided with a double horizontal pendulum R', the said axis R also having a friction-disk R², to which the brake is applied.

To the angular cross-piece g⁴ is fixed another cross-plate g⁵, upon the horizontal part of which is screwed an auxiliary armature S, composed of the strip s and the soft-iron cross-piece S'. This auxiliary armature is not rigidly fixed to the plate g⁴, but an inclination of the end upon which S' is fixed, caused by attraction of the magnet F for the

soft-iron piece S' , is made possible by the elasticity of the cross-piece g^5 , which elasticity tends to keep the auxiliary armature at a distance from the electromagnet. The other extremity of the auxiliary armature S is provided with a set-screw T , whose point is pressed down upon the friction-disk R^2 . The set-screw point T' , fixed in a support U , attached to the one side plate g , serves to limit the upward motion of the armature S .

The apparatus works as follows: The carbons being normally separated, as described, the current is sent into the two wires $o o'$. The potential difference between the two carbons being sufficiently great, the magnetic coils will be strongly excited by the shunt-circuit, so that the armature, by means of its pole-pieces G or its ends ff , is attracted and turned around its fulcrum-points $d d$, by which means the carbon-points are brought together; but as the soft-iron pieces ff now form part of the magnetic cores they will also attract the auxiliary armature S , whose opposite extremity will thereby be lifted, the set-screw T raised, and the friction-disk R^2 released. The weight M will therefore be allowed to sink down like an ordinary clock-weight and its descending movement exactly regulated by the escapement and the pendulum R' , above described. At the same time the lower carbon is raised by the clockwork, and the upward pull of cord m and their two ends will approach until they will come in contact with one another. The potential difference between the carbons will now fall off and the shunt-current in the magnetic coils of F will also be diminished, in consequence of which the spring L will draw back the armature and turn it around the fulcrum $d d$, and the auxiliary armature S will also again press with its extremity against the friction-disk R^2 and hold the clock-work and carbons steady.

When the armature G is turned by the spring L and the top carbon is raised, the arc will appear between the carbons. Consequently the shunt-current is increased again and the main armature is attracted by the magnet; but at first the shunt-current will not be strong enough to attract the auxiliary armature. Moreover, the attraction of the main armature will not be a sudden one, but

the approach of the armature to the cores will take place gradually and proportionally to the length of the arc and the increase of potential difference and of shunt-current 55 hereby caused. If, finally, the latter becomes intense enough, the auxiliary armature is also attracted, the clockwork is released, and the distance between the carbons hereby regulated until the potential difference, and therefore also the shunt-current, is diminished. 60

The clockwork is wound up by drawing down the carbon-holder N , whereby the weight M is lifted, which is done whenever carbons are put into the holders. 65

It is obvious that many slight alterations may be made in the parts and combinations of parts hereinbefore described, and hence I would have it understood that I do not strictly confine myself to the specific construction 70 shown.

I claim as my invention and desire to secure by Letters Patent—

1. In an electric-arc lamp the combination of an electromagnet included in a shunt-circuit of a main armature having side plates and a clockwork supported thereon carrying a ribbon from which the carbon is supported, a horizontal pendulum, a friction-disk upon the axis thereof, and an auxiliary armature 80 elastically supported upon the main armature controlled by said electromagnet and having an adjustable break-screw to press upon said friction-disk, substantially as described. 75

2. In an electric-arc lamp, the combination 85 with the lamp-frame comprising a reflector ring-shaped bottom C , an upper plate D , a shunt-magnet armature and gear supported upon said plate, a gear-operating weight M , insulated from carrying the upper carbon and 90 guided by wires M' , a rod N , supporting the lower-carbon holder and insulated from the frame and guide-wires M' and n^2 extending between the bottom C and plate D , substantially as described. 95

In testimony that I claim the foregoing as my invention I have signed my name in presence of two subscribing witnesses.

HERMANN BÄURLIN.
